UNCOUPLING APPARATUS FOR PILOT COUPLERS

Herman G. Larson, Altoona, Pa., assignor to The Pennsylvania Railroad Company, Philadelphia, Pa., a corporation of Pennsylvania

Application July 17, 1936, Serial No. 91,158

4 Claims. (Cl. 213—162)

This invention relates to an uncoupling apparatus useful for a pilot coupler, and though capable of a variety of uses, it is especially adapted for use with a locomotive pilot coupler of the disappearing type.

Heretofore it has been proposed to employ a swinging coupler at the pilot of the locomotive which can be moved from a service position, wherein it extends forwardly from the pilot, to a housed position wholly within the pilot, the housing of the coupler being accomplished in such manner as to maintain the continuity or smoothness of the deflecting surfaces at the front of the pilot. One difficulty presented by the use of a disappearing coupler of this type is that the standard forms of uncoupling apparatus are not designed to take care of such a degree of radial movement of the coupler. It has been proposed to employ detachable links or the like to be disconnected when the coupler is housed and to be connected when the coupler is in service. Such a method is cumbersome and disadvantageous, for it is desirable that the uncoupling rigging be at all times in readiness for service with the parts securely assembled together, and it is particularly important to guard against the possibility of the uncoupling apparatus being inoperative, by reason of the disconnection, accidental or otherwise, of any of its parts, at a time when it is desired to effect uncoupling.

It has also been proposed to surround the pilot of a locomotive with a streamlined casing, and when such a casing is employed the standard forms of uncoupling apparatus are not altogether satisfactory because of difficulties in gaining access to the handles of the operating levers, and operating the same through doors in the casing.

The object of the present invention is to provide a form of uncoupling apparatus which overcomes the above recited difficulties. More specifically, the apparatus of this invention is designed to take care of the movement of a disappearing coupler without requiring disconnection of any parts, and it is further characterized by the provision of an operating rod which is adapted to slide in the direction of its length, rather than to be rotated about its central axis, and thus to make it easier to manipulate the handle of the operating rod when access to the apparatus is gained through a streamlined casing.

Other objects and advantages of the present invention, including those derived from the use of means for minimizing frictional resistance, will be apparent from the description hereinafter

set forth of one example or embodiment of the invention, having reference to the accompanying drawings.

Of the drawings:

Fig. I represents a front elevation of a locomotive pilot embodying my invention.

Fig. II represents a plan view of the same, in which the coupler is represented in full lines in its service position and in dot-and-dash lines in its housed position within the pilot.

Fig. III represents a cross section, taken as indicated by the lines III—III of Fig. II.

Fig. IV represents a perspective view of a stop pin for limiting radial movement of the coupler when in service.

Fig. V represents an enlarged detail view of a handle and latch mechanism, taken as indicated by the lines V—V in Fig. II, by means of which the coupler may be locked in its housed position.

Fig. VI represents a perspective view of the uncoupling apparatus with the top deck of the pilot shown in dot-and-dash lines.

Fig. VII represents an enlarged view of a portion of the lifter bar of the uncoupling apparatus, taken as indicated by the lines VII—VII of Fig. II, showing the manner in which rollers are applied thereto at the points of engagement with the operating rods; and,

Fig. VIII represents an enlarged cross section of one of the operating rods, taken as indicated by the lines VIII—VIII of Fig. II, showing the manner in which a roller is applied thereto for sliding engagement with the top deck of the pilot.

With reference to Figs. I and II of the drawings, there is shown a locomotive front end construction which includes an integrally cast pilot and pilot beam. In the particular example shown, the pilot and pilot beam are made up of sections bolted or otherwise secured together, there being a central pilot member 1 and wings 1a, 1b forming lateral extensions of the pilot and pilot beam. It will be understood, however, that the invention being primarily concerned with the uncoupling apparatus, hereinafter described in detail, the particular construction shown in the drawings constitutes merely one example of a locomotive front end construction to which my invention may be advantageously applied.

The top surfaces of the central pilot member 1 and of the wings 1a, 1b, together with the deck plate 2, form a flat deck upon which various equipment may be mounted, including the uncoupling apparatus which is comprehensively designated at 3. At the front of the pilot, the

walls 4a, 4b converge forwardly toward the center line of the locomotive, and present solid deflecting surfaces well adapted to cast an object clear of the track when struck by the locomotive.

5 Desirably steps 5 project laterally at each side of the structure near the base thereof, and additional steps 6 are formed in the wing castings 4a, 4b at a higher elevation. In an obvious manner the steps 5, 6 permit a man to mount to the flat 10 deck at the top of the pilot or to gain access to the uncoupling apparatus 3.

In order to accommodate the coupler 7, a housing 8 is provided within the central pilot member 1. As shown most clearly in Fig. III, the pilot 15 member 1 is cellular in construction, and the housing 8 constitutes a compartment bounded at the top and bottom and on all sides, except the front, by webs or walls of the casting. The housing 8 is of such shape that the coupler 7 may 20 be wholly accommodated therein when not in service. At the base of the housing 8 there is a horizontal shelf 9 with an annular boss 10 surrounding the coupler center pin 11.

A cover plate 12 is formed integrally with the 25 coupler 7 and accurately fits the opening at the front of the coupler housing 8. The cover plate 12 moves with the coupler 7 about the center pin 11. It may be locked in closed position by means of a handle 14 and latch mechanism, the 30 details of which are represented in Fig. V. At the inside of the cover plate 12, there is a latch member 15 which rotates with the handle 14 and which is adapted to engage behind the edge of the wall 4a.

35 In order to limit radial motion of the coupler 1 in a counterclockwise direction, a stop pin 16 is employed, the pin 16 being normally housed in a pocket 17, and secured against removal by means of a collar 18 at the base thereof, as shown most 40 clearly in Fig. IV. In its housed position, represented in Fig. III, the top of the stop pin 16 is beneath the bottom of the coupler 7. When the coupler is extended forwardly to service position, the pin 16 is raised, and turned to the position represented in Figs. I, II and IV, wherein 45 its enlarged top portion, which is of elliptical cross section, rests on the shelf 9 and bears against an upstanding abutment 20. To return the stop pin 16 to housed position, the pin is lifted 50 and rotated clear of the abutment 20 and then dropped into the pocket 17. Radial movement of the coupler 7 in the other direction is limited by the side wall of the coupler housing 8.

The uncoupling apparatus 3 is most clearly 55 represented in Fig. VI. It comprises generally a pair of uncoupling pull rods 21 which extend transversely across the top deck of the pilot, a lifter bar 22 having a fixed end pivotally mounted on the pilot, and connecting members including 60 an extension arm 23 and a link 24 which are attached to the free end of the lifter bar and join the lock lifting means of the coupler 7. The lock-lifting or unlocking means is operated by an upward actuating movement. The operating rods 65 21 are slidable in the direction of their length within guides 25 bolted to the top of the pilot. Each operating rod 21 has at the outer end thereof an upturned handle 26, by means of which an uncoupling operation is effected, and at the other 70 end an upwardly inclined arm 27 which freely engages the lifter bar 22 from beneath the same. The upturned arms 27 of the two operating rods 21 cross each other immediately below the lifter bar 22 and engage a pair of rollers 28 75 on the lifter bar 22. As shown most clearly in

Fig. VII, the rollers 28 are secured to the intermediate portion of the lifter bar 22 by means of cotter pins 29, with washers 30 interposed between the pins and the rollers.

Adjacent to the rollers 28 a pair of vertical 5 guide members 32 are affixed to the top deck of the pilot. The guide members 32 may conveniently take the form of a flat strip bent to a right angle, and together they confine movement of the intermediate portion of the lifter bar 22 to 10 a vertical plane which is coincident with the pivotal axis of the coupler 7. At its fixed end, the lifter bar 22 has an enlarged portion 33 flattened and provided with an aperture through which a pivot bolt 34 passes. The pivot bolt is supported 15 in brackets 35. In an obvious manner, sliding movement of either of the operating rods 21 outwardly in the direction of its length causes an upward movement within the guides 32 of the free end of the lifter bar 22. The free end of the 20 lifter bar 22 has a flattened portion 36 provided with an aperture through which a bolt 37 is inserted. The bolt 37 is fixed to a yoke portion 38 of the extension arm 23. It will be noted that the bolt 37 is directly above and in line with 25 the pivotal axis of the coupler center pin 11, see Figs. II and III. When the coupler 7 moves from its forwardly extended or service position to its housed position, the link 24 is accommodated within an arcuate opening 39 at the top of the 30 coupler housing 8. When the coupler 7 swings horizontally about its upright pivot axis 11, the guides 32, 32 brace the lifter bar 22 as against side stresses from the extension member 23, pivoted or articulated to it about the upright axis 35 37 aligned with the axis 11.

On each operating rod 21 there is provided a pair of rollers 40 which engage the flat deck at the top of the pilot. When it is desired to effect uncoupling, the operator grasps the handle 26 40 at either side of the locomotive, and pulls the same outwardly in a direction transverse to the center line of the locomotive. The rollers 40 aid materially in the manipulation of the operating rods 21. As clearly shown in Fig. VIII, each 45 roller 40 is mounted on a bushing 41 and is accommodated between a pair of washers 42. A bolt 43 secures the parts to the operating rod 21. Each pull rod 21 lifts the lifting bar 22 and unlocks the coupling quite independently of the 50 other, by means of its own independent inclined arm 27, without at all affecting the other rod 21 or its operability by a pull. This is important; because a man pushing on such a rod in the effort to operate a mechanism that sticks may 55 fall on a rail between the cars when the mechanism suddenly yields to his effort.

The operation of the uncoupling apparatus will be apparent from the above description of its component parts. It will be particularly observed that all parts of the apparatus are 60 permanently connected together, and that there is no occasion for disconnection of any part when it is desired to house the coupler 7 within the coupler housing 8. When the coupler 7 is moved 65 to housed position, the extension arm 23 moves about the pivot bolt 37 in line with the axis of the center pin 11, and the link 24 moves inwardly through the arcuate opening 39. When the coupler 7 is thus housed, its cover plate 12 fills the 70 opening at the front of the coupler housing 8 and forms with the front walls 4a, 4b smooth continuous deflecting surfaces.

Moreover, it will be observed that the front 75 end construction herein described is particu-

larly well adapted for use in conjunction with an exterior streamlined casing. When such casing (not shown) is employed, it may surround the construction close to the front surfaces of the pilot and yet not interfere with the operation of the uncoupling apparatus, access to the handles being gained through small doors in the casing. One example of the streamlined casing of this character is shown in the pending application of William G. Myer and David R. Ohlwiler, Serial No. 91,153, filed July 17, 1936.

While I have described herein one particular example of a locomotive front end construction embodying uncoupling apparatus of this invention, it will be apparent, especially to those skilled in the art, that various changes may be made in the pilot and coupler structure, and in the form of the parts of the uncoupling apparatus, without departing from the spirit of the invention 20 as defined in the annexed claims.

Having thus described my invention, I claim:

1. The combination with a railway vehicle end frame and coupling mechanism, including a coupler associated with said end frame and having unlocking means operable by an upward actuating movement, and a lifter bar operatively connected to said unlocking means for actuating the same; of separate transverse pull rods associated with said end frame and extending one to each side thereof, each of said pull rods being operable only from one side of said end frame, and means operable by a pull on either of said rods, independently of the other rod, for lifting said lifter bar while leaving said other rod substantially unmoved, so that the unlocking means of the coupler may be operated by a pull on the rod from either side of the car without affecting the pull rod extending to the other side of the car and its operability by a pull.

2. The combination with a railway vehicle end frame and coupling mechanism, including a coupler associated with said end frame and having unlocking means operable by an upward actuating movement, and a lifter bar operatively connected to said unlocking means for actuating the same; of separate transverse pull rods associated with said end frame and extending

one to each side thereof, each of said pull rods being operable only from one side of said end frames, means for lifting said lifter bar connected to one of said pull rods and operable by a pull thereon, and means independent of that aforesaid and for lifting said lifter bar connected to the other of said pull rods and operable by a pull thereon, while the first mentioned pull rod remains substantially unmoved, so that the unlocking means of the coupler may be operated by 10 a pull on a rod from either side of the car without affecting the pull rod extending to the other side of the car and its operability by a pull.

3. The combination with a railway vehicle coupling mechanism including a coupler pivoted to swing about an upright axis and provided with unlocking means operable by an upward actuating movement, a lifter bar for actuating said unlocking means, and operating means for lifting said lifter bar; of an extension member pivoted to said lifter bar about an upright axis aligned with the aforesaid upright axis of said coupler; and means connecting said extension member to the unlocking means of said coupler, so that the latter may be operated by said operating means in any horizontal position of the coupler.

4. The combination with a railway vehicle coupling mechanism including a coupler pivoted to swing about an upright axis and provided with unlocking means operable by an upward actuating movement, a lifter bar pivoted to swing upward relative to said coupler, for actuating said unlocking means, and operating means for swinging said lifter bar as aforesaid; of an extension member pivoted to said lifter bar about an upright axis aligned with the aforesaid upright axis of said coupler; means connecting said extension member to the unlocking means of said coupler, so that the latter may be operated by said operating means in any horizontal position of said coupler, or even during its swinging movement; and upright guides coacting with said lifter bar, for bracing it when said extension member swings about its upright pivotal axis with the swinging of the coupler.

HERMAN G. LARSON.
